UNITED STATES PATENT OFFICE.

EVERARD L. JOHNSON, OF PATCHOGUE, NEW YORK.

FLASH-LIGHT GUN.

Application filed February 26, 1921, Serial No. 448,157. Renewed April 4, 1922. Serial No. 549,499.

To all whom it may concern:

Be it known that I, EVERARD L. JOHNSON, a citizen of the United States, and residing at Patchogue, Long Island, in the county of 5 Suffolk and State of New York, have invented certain new and useful Improvements in Flash-Light Guns, of which the following is a specification, such as will enable those skilled in the art to which it appertains to 10 make and use the same.

This invention relates to flashlight guns and particularly to devices of this class adapted for use by professional as well as amateur photographers in studios and homes, 15 and the object of the invention is to provide a gun or device which will ignite the explosive powder commonly employed in devices of this class in such manner that the ash or dust thereof will not come in contact 20 with the operative mechanisms of the gun; a further object being to provide improved means for creating a spark for igniting the explosive powder employed; and with these and other objects in view the invention consists in a flashlight gun of the class specified 25 which is simple in construction and operation and efficient in use, and which is constructed and operated as hereinafter described and claimed.

30 The invention is fully disclosed in the following specification, of which the accompanying drawing forms a part, in which the separate parts of my improvement are designated by suitable reference characters in 35 each of the views, and in which:

Fig. 1 is a longitudinal sectional view through my improved flashlight gun and showing the parts thereof in a normal position;

40 Fig. 2 a partial section on the line 2—2 of Fig. 1;

Fig. 3 a view similar to Fig. 1 but showing the parts of the gun in a different position and showing a detail of the construction not 45 shown in Fig. 1;

Fig. 4 a partial section on the line 4—4 of Fig. 3;

Fig. 5 a partial section on the line 5—5 of Fig. 3;

50 Fig. 6 a partial section on the line 6—6 of Fig. 3 on an enlarged scale; and

Fig. 7 a partial section on the line 7—7 of Fig. 3 and on an enlarged scale.

In practice, I provide a suitable and approximately rectangular casing 10 having a 55 back wall 11, side walls 12 and top and bot-

tom walls 13 and 14, and the bottom wall 14 is offset as shown at 15. The front of the casing 10 is open and adapted to be closed by a suitable cover plate 16 secured in position 60 in any desired manner.

The back wall 11 of the casing is provided at its lower edge with an outwardly and upwardly directed trough 17 which extends the full length of said casing, as shown in Fig. 65 5 and in which the explosive flash powder is adapted to be placed.

A spark creating or generating device 18 is mounted within the casing and, in the form of construction shown, said device 70 comprises an approximately triangular plate member 19 rotably mounted on a stub shaft 20 carried by the back wall 11 of the casing. The outer face of the plate member 19 is arc-shaped in form and provided with a file or 75 other roughened facing 21 adapted to operate in connection with a piece of flint or the like 22 mounted in a suitable keeper 23 and normally forced inwardly by a spring 24, the tension of which is controlled by a screw 80 25 extending through the bottom 14 of the casing. The plate member 19 is provided with an arm 26 with which one end of a spiral spring 27 is connected, the other end of said spring being secured to a post 28 on the back 85 wall of the casing, and said spring serves to actuate the plate member 19, as herein-after described.

One corner portion of the plate member 19 is provided with a projecting finger 29 in 90 connection with which the hook-shaped end 30 of a lever 31 operates, said lever being pivotally mounted in the casing as shown at 32 and the other end 33 of said lever is provided with a light spiral spring 34 the 95 tension of which is controlled by a screw 35 which extends through the offset portion 15 of the bottom wall of the casing and provided with a lock nut 36. A stop 37 is employed for limiting the downward movement 100 of the end portion 33 of the lever.

The offset portion 15 of the bottom wall 14 is provided with a cylinder 38 which extends into the casing and is provided with an outwardly directed nipple 39. A piston 105 40 is mounted in the cylinder 38 and a flexible tube 41 is mounted upon the nipple 39. The tube 41 forms a part of, or is connected with the usual air bulb for actuating the shutter of a camera, as is the common practice in devices of the class under consideration. The piston 40 is located beneath the

end portion 33 of the lever 31 and serves to raise said end portion of the lever into the position shown in Fig. 3.

The back wall 11 of the casing is provided with a tubular member 42 which opens inwardly into the casing 10 and outwardly through said back wall through an aperture 43. The inner end portion of the tubular member 42 is provided with an elongated slot 44 through which the facing 21 of the plate member 19 is adapted to pass, as clearly illustrated in Fig. 3, and said tubular member is provided with another slot 45 in connection with which a shutter device 46 operates. The shutter device 46 is pivoted to the back wall 11 of the casing, as shown at 47, and said shutter is provided with an arm 48 carrying an antifriction roller 49. The shutter device 46 is held in a normal position similar to that shown in Fig. 1 by a spring 50; and a stop pin 51 limits the movement of said shutter device in one direction.

A shoe or cam member 52 is adjustably mounted in connection with the plate member 19, said shoe being provided with screws 53 which pass through elongated apertures 54 in said plate member as illustrated in Figs. 1 and 3 of the drawing, and said shoe or cam member 52 is provided with an offset portion 55, and in the operation of the plate member 19 the anti-friction roller 49 passes over the top face of the shoe or cam member 52 and the off-set portion 55 thereof, which operation causes the shutter device 46 to be moved from the position shown in Fig. 1 to that shown in Fig. 3. The plate member 19 is also provided with a finger piece 56 which extends outwardly through and operates in an arc-shaped aperture 57 in the cover plate 16, and this finger piece serves to limit the movement of said plate member in both directions and provides means for setting the gun or returning the parts thereof to their normal position.

The operation of my improved gun will be readily understood from the foregoing description when taken in connection with the accompanying drawing and the following statement. As previously stated, the position of the parts shown in Fig. 1 is their normal position, in which the plate member 19 is held in position against the tension of the spring 27 by the engagement of the hook-shaped end 30 of the lever 31 with the finger piece 29, and the shutter device 46 is held in the position shown in said figure by the spring 50 and the communication through the tubular member 42, or the aperture 43 thereof, is open. When it is desired to use the device the required amount of the explosive or flash powder is placed in the trough 17, after which the gun is placed or mounted in the desired position, or in connection with a suitable flash bag, if desired,

and the operation of the shutter of the camera in the usual manner through the usual air bulb will cause the piston 40 to be moved upwardly into the position shown in Fig. 3, which operation actuates the lever 31 to disengage the hook-shaped end portion 30 thereof from the finger piece 29, and the spring 27 will then actuate the plate member 19 to move it from the position shown in Fig. 1 to that shown in Fig. 3, in which operation the passage of the file or other facing 21 over the spring-actuated flint 22 will generate or create sparks which are directed to the explosive or flash powder in the trough 17 through the tubular member 42 and the aperture 43 in the back wall 11 of the casing. In the above operation of the plate member 19 the shutter device 46 is moved into an operative position to close the communication through the tubular member 42, as clearly shown in Figs. 3 and 7 of the drawing, whereby in the explosion of the powder, the dust or ash thereof will not be permitted to pass backwardly into the casing 10 through the tubular member 42 and thus come in contact with the various parts of the gun mounted within the casing, and especially the file or other facing 21 which would cause or render the device inoperative.

It has been found by experience that with guns of this class now upon the market and in use, the operation thereof is unsuccessful and unreliable due to the fact that the spark generating or creating elements of such guns become useless by reason of the fact that the dust or ash of the exploded powder collects upon the various parts of the gun, and especially the sparkling elements thereof, and such guns can only be used on one or two successive occasions, after which they must be taken apart and thoroughly cleaned.

With my improved gun, however, it will be seen that the difficulties experienced with the present type of guns is obviated, but if by any chance the dust or ash of the powder should pass into the casing through the tubular member 42 this dust or ash would collect upon the upper end portion of the file facing and leave the lower end portion thereof in a free and clear state, and due to the fact that the sparks are generated at the lower end portion of said facing, the collecting of dust or ash on the upper end of said facing will not effect the operation of the gun, and it is for this reason that the triangular segmental plate member 19 is employed.

It will be understood that by adjusting the shoe or cam member 52, the position of the offset portion 55 thereof may be so regulated as to close the shutter device 46 at the proper time, or immediately after the powder has been exploded and by properly adjusting the spring 34 which normally

holds the lever 31 and piston 40 in proper position, the plate member 19 may be released so as to ignite the explosive powder at the same time as the shutter of a camera is actuated and due to the fact that the shutters of cameras are operated by varying air pressures from an air bulb, it is necessary to provide the spring 34 so that the gun may be regulated to suit the different 10 cameras.

It will be understood that when the air bulb which actuates the piston 40 is released the lever 31 will be returned to its normal position by the spring 34 and the 15 plate member 19 and shutter device 46 will be returned to their normal position by the operator who moves the projecting finger piece 56 upwardly in the aperture 57, in which operation the finger 29 will be again 20 caught or engaged by the hook-shaped end portion 30 of the lever 31 and the gun is again in position for use.

It will be apparent that I am not necessarily limited to any specific form of shutter 25 device 46 nor to the means herein shown and described for releasing and actuating the spark generating elements, and various changes in and modifications of the details of construction herein shown and described 30 may be made within the scope of the appended claims, without departing from the spirit of my invention or sacrificing its advantages.

Having fully described my invention, 35 what I claim as new and desire to secure by Letters Patent, is:—

1. A flashlight gun comprising a suitable support provided with a powder receiving receptacle, a segmental member pivotally mounted in connection with said support and provided with a file or roughened facing, a flint support, a spring for operating a flint placed in said support and in connection with which said file or roughened facing operates, 45 means for holding said segmental member in an inoperative position, means whereby the releasing of said member will cause it to move over said flint to generate sparks, and means for directing said sparks to said 50 receptacle.

2. A flashlight gun comprising a suitable support provided with a powder receiving receptacle, a segmental member pivotally mounted in connection with said support and provided with a file or roughened facing, a flint support, a spring for operating a flint placed in said support and in connection with which said file or roughened facing operates, means for holding said 55 segmental member in an inoperative position, means whereby the releasing of said member will cause it to move over said flint to generate sparks, means for directing said sparks to said receptacle, and means in operative connection with said last named means

for automatically closing the communication to said receptacle when the powder therein has been ignited.

3. A device of the class described comprising a suitable casing having an external 70 powder receiving receptacle in communication with said casing through a port or passage, a segmental member pivotally mounted within said casing and provided with a roughened facing adapted to operate in connection with a piece of spring-actuated flint for generating sparks which are passed through said port or passage into said receptacle, tensional means for operating said segmental member in one direction, means 80 for holding said member in an inoperative position against the action of said tensional means, and means for releasing said last named means to cause said member to be actuated by said tensional means. 85

4. A device of the class described comprising a suitable casing having an external powder receiving receptacle in communication with said casing through a port or passage, a segmental member pivotally mounted 90 within said casing and provided with a roughened facing adapted to operate in connection with a piece of spring-actuated flint for generating sparks which are passed through said port or passage into said receptacle, tensional means for operating said segmental member in one direction, means 95 for holding said member in an inoperative position against the action of said tensional means, means for releasing said last named means to cause said member to be actuated by said tensional means, and a shutter device 100 adapted to be automatically operated by said segmental member.

5. A device of the class described comprising a suitable casing having an external powder receiving receptacle in communication with said casing through a port or passage, a segmental member pivotally mounted within said casing and provided with a 105 roughened facing adapted to operate in connection with a piece of spring-actuated flint for generating sparks which are passed through said port or passage into said receptacle, tensional means for operating said segmental member in one direction, means for holding said member in an inoperative position against the action of said tensional means, means for releasing said last named means to cause said member to be actuated 110 by said tensional means, a shutter device adapted to be automatically operated by said segmental member, tensional means for holding said shutter device in an inoperative position, and adjusting means on said segmental member for regulating the operation of said shutter device. 120

6. A device of the class described comprising a suitable casing having an external 125 powder receiving receptacle in communica- 130

- tion with said casing through a port or passage, a segmental member pivotally mounted within said casing and provided with a roughened facing adapted to operate in connection with a piece of spring-actuated flint for generating sparks which are passed through said port or passage into said receptacle, tensional means for operating said segmental member in one direction, means for holding said member in an inoperative position against the action of said tensional means, means for releasing said last named means to cause said member to be actuated by said tensional means, a shutter device adapted to be automatically operated by said segmental member, tensional means for holding said shutter device in an inoperative position, adjusting means on said segmental member for regulating the operation of said shutter device, and means whereby said segmental member may be manually returned into its normal position.
7. A device of the class described comprising a suitable casing having an external powder receiving receptacle in communication with said casing through a port or passage, a rotatable plate member mounted within said casing, tensional means for operating said member in one direction, a lever mounted in said casing and in operative connection with and adapted to hold said plate in position against the action of said tensional means, adjustable tensional means for controlling the movement of said lever, means for operating said lever to release said plate member, and means in the casing and on said plate for generating sparks in the movement of said plate member by said tensional means, said sparks being adapted to pass outwardly through said casing through said port or passage and into said receptacle.
8. A device of the class described comprising a suitable casing having an external powder receiving receptacle in communication with said casing through a port or passage, a rotatable plate member mounted within said casing, tensional means for operating said member in one direction, a lever mounted in said casing and in operative connection and adapted to hold said plate in position against the action of said tensional means, adjustable tensional means for controlling the movement of said lever, means for operating said lever to release said plate member, means in the casing and on said plate member for generating sparks in the movement of said plate member by said tensional means, said sparks being adapted to pass outwardly through said casing through
- said port or passage and into said receptacle, a shutter device adapted to close said port or passage, and adjustable means on said plate member for actuating said shutter device.
9. A flashlight gun comprising spark generating elements mounted within a closed casing, said casing having an external powder receiving receptacle, means for placing said sparking elements in communication with said receptacle, and means for automatically closing said communication when the powder in said receptacle has been ignited by said sparking elements.
10. A device of the class described comprising a closed casing having an external powder receiving receptacle in communication with the interior thereof, means within the casing for generating sparks which are adapted to pass through said communication to said receptacle, and means for controlling said communication.
11. A device of the class described comprising a closed casing having an external powder receiving receptacle in communication with the interior thereof, means within the casing for generating sparks which are adapted to pass through said communication to said receptacle, and automatically operated means for closing said communication when the powder in said receptacle has been ignited.
12. A device of the class described comprising a closed casing having an external powder receiving receptacle in communication with the interior thereof, means within the casing for generating sparks which are adapted to pass through said communication to said receptacle, automatically operated means for closing said communication when the powder in said receptacle has been ignited, and adjustable means for controlling the operation of said last named means.
13. A device of the class described comprising a closed casing having an external powder receiving receptacle in communication with said casing through a port or passage, spark generating elements within said casing, and the sparks of which are adapted to pass outwardly through said port or passage into said receptacle, and an automatically operated shutter device for closing said port or passage.
- In testimony that I claim the foregoing as my invention I have signed my name in presence of the subscribing witnesses this 23rd day of Feb., 1921.
